J. E. Sturdy,
Sawing Shingles.

No. 26,302.

Patented Nov. 29, 1859.

J. E. Sturdy

UNITED STATES PATENT OFFICE.

J. E. STURDY, OF AUGUSTA, MAINE.

SHINGLE MACHINE.

Specification of Letters Patent No. 26,302, dated November 29, 1859.

To all whom it may concern:

Be it known that I, J. E. STURDY, of 5 Augusta, in the county of Kennebec and State of Maine, have invented a new and Improved Planing Attachment for Shingle Machines; and I do hereby declare that the following is a full, clear, and exact description of the same, reference being had to the annexed drawings, making a part of this 10 specification, in which—

Figure 1, is a side view of a shingle machine with my invention applied to it. Fig. 2, a transverse vertical section of ditto, taken in the line α, α Fig. 3. Fig. 3, a plan 15 or top view of ditto.

Similar letters of reference indicate corresponding parts in the several figures.

This invention is designed to be attached to that class of shingle machines, in which 20 a circular saw, and reciprocating bolt-carriage are used.

The object of the invention is to obtain a planing device that will operate automatically by the movement of the bolt carriage 25 and perform the desired work, to wit, the planing of the face side of the shingles as they are sawed from the bolt without any additional aid or attendance in the manipulation of the machine to which the invention 30 is applied.

To enable those skilled in the art to fully understand and construct my invention, I will proceed to describe it.

A, represents a rectangular framing on 35 the upper part of which a saw-arbor B, is placed in suitable bearings, the saw C, being on its inner end.

D, D, are two parallel ways placed longitudinally on the framing A, and at right 40 angles with the saw arbor B.

E, is a bolt carriage which is simply a quadrilateral frame mounted on wheels a , the peripheries of which are grooved and work on the ways D, D.

45 On the carriage E, two transverse parallel bars b , b , are placed to which the guides c , c , of a head block F, are attached. To this head block the usual jaws d , d , are attached and to each end of the head block a rack 50 bar e , is attached by a pivot. In the outer ends of the bars b , b , a shaft G, is placed, said shaft having a tappet c' , at each end, see dotted lines Figure 1, each tappet being provided with two teeth and the two tappets placed in reverse positions and directly 55 under the racks e . On the shaft G, there is

placed two cams f , f , in reverse positions and a ratchet g , is also placed on said shaft, said ratchet having a pawl h , engaging with it intermittently, which pawl is attached to 60 the front part of a lever H, at the outer side of the bolt carriage, see Fig. 1.

To the inner side of the bolt-carriage E, two arms or guide bars I, I, are attached by pins at opposite ends. Each guide I, 65 has a bar J, connected to it by a joint i , and the outer ends of the bar J, work in grooves made transversely in the outer side piece of the bolt carriage and in line with the cams f , f . The guides I, I, are attached to the 70 bolt-carriage one directly over the other as shown in Fig. 2, and the bars J, J, are connected to the guides near their outer ends.

On the framing A, and just in front of the saw C, an upright K, is placed. This 75 upright is attached to a horizontal plate j , which is fitted in a proper guide k , secured to a traverse bar l of the framing. The upright K, has two horizontal arms l , l , attached to it and these arms form the bearings for a rotary planer L, which is formed of knives m , attached to the opposite sides of a polygonal head n . To the lower part of the head a pulley o , is attached, and to the lower end of the upright K, a cord or 80 chain p , is secured. Said cord or chain passing over a pulley or guide q , and having a weight r , attached to its lower end, said weight having a tendency to keep the lower bearing in contact with the outer sides 85 of the guides I, I.

The bolt-carriage E, is operated by a rack and pinion as usual in order to feed the bolt to the saw, and by means of an ordinary clutch arrangement the pinion is disengaged 90 from its shaft M, in order that the bolt-carriage may be readily gigged back. The saw C, planer L, and shaft M, may be rotated in any proper way.

The operation is as follows. The bolt 100 shown in red is secured between the jaws d , d , of the head block F, and as the bolt carriage E, moves in the direction indicated by the arrow Fig. 3, a shingle is sawed from the bolt. When the carriage E, reaches the 105 termination of its forward movement and the shingle sawed from the bolt, the carriage is gigged back and the head block F, moved forward at one end in order that the bolt may be presented obliquely to the saw. The head block F has its ends moved alternately owing to the position of the tappets 110

c' on the shaft *G*, and the latter is rotated a certain distance just previous to the termination of each gigging back motion in consequence of the lever *H*, striking a pin *a'* on the framing and thereby actuating the pawl *h*. By this arrangement the shingles will be cut with their butts alternately from either side of the bolt. The above operation is substantially the same as that of many shingle machines in which circular saws are used.

Each time the shaft *G*, is turned by the pawl *h*, the guides *I*, *I*, are actuated one by a cam *f*, and the other by the pressure of the lower arm *l*, of the upright *K*, against it. The guides *I*, *I*, guide alternately the planer *L*, for they are alternately acted upon by the cams *f*, to assume a parallel position, with the face of the bolt so that the planer *L*, will be made, as the carriage *E*, and bolt are moved forward toward the saw, to rotate in a plane parallel

with the face of the bolt in either of its positions, and the planer will consequently perform its work in either position of the bolt.

I do not claim any of the parts herein described pertaining to the sawing of the shingles from the bolt, for they are in present use and are not of my invention but,

I do claim as new and desire to secure by Letters Patent,

The employment or use, in connection with the shingle-sawing machine described, of the guides *I*, *I*, attached to the bolt-carriage *E*, and actuated alternately to perform their proper function to the planer *L*, the whole being arranged substantially as and for the purpose set forth.

J. E. STURDY.
